STRUCTURE FOR FURNITURE AND THE LIKE

Justin J. Wetzler, Evanston, Ill., assignor to The Englander Company, Inc., Chicago, Ill., a corporation of Delaware

Application June 21, 1954, Serial No. 438,256

5 Claims. (Cl. 155—180)

The present invention relates to a novel structure for use in furniture such, for example, as chairs, divans, box springs and vehicle seats, and more particularly, to a novel frame structure to which covering fabric sections and the like may be attached. This application is a continuation in part of my co-pending application Serial No. 419,736, filed March 30, 1954.

As set forth in the above mentioned co-pending application, wood has heretofore generally been used for providing frames for box spring structures and various pieces of furniture, but such wooden frames are subject to a number of disadvantages which may be overcome by providing metal frames of the type described in the above mentioned co-pending application. One problem that arises when utilizing metal frames of the type contemplated herein is the attachment of covering fabric sections or panels to the metal frame since such usual devices as tacks and staples cannot be used. It is, therefore, a primary object of the present invention to provide a novel structure including a metal frame member and a fabric panel, which structure is formed so that the fabric panel may be readily attached to the metal frame in a manner that will permit the fabric to have a neat, unwrinkled appearance.

Another object of the present invention is to provide a novel metal frame member of the above described type with means for gripping or securing a fabric panel or section substantially through the entire length of the frame member whereby the fabric panel may be uniformly held along its length so as to reduce any possibility of bulges or wrinkles appearing therein.

Still another object of the present invention is to provide a novel metal frame member of the above described type having means thereon into which a portion of a fabric panel may be easily inserted, which means is operable positively to prevent withdrawal of the fabric.

Other objects and advantages of the present invention will become apparent from the following description and the accompanying drawings wherein:

Fig. 1 is a fragmentary perspective view showing a structure embodying the principles of this invention;

Fig. 2 is an enlarged fragmentary cross sectional view taken along line 2—2 in Fig. 1;

Fig. 3 is a further enlarged fragmentary cross sectional view similar to Fig. 2 and showing the novel structure in greater detail;

Fig. 4 is a perspective view of an element adapted to be secured to a metal frame member for attaching a fabric panel to the frame member;

Fig. 5 is a fragmentary cross sectional view similar to Fig. 3 and showing a slightly modified form of the present invention;

Fig. 6 is a fragmentary perspective view showing another modified form of the present invention;

Fig. 7 is an enlarged fragmentary cross sectional view taken along line 7—7 in Fig. 6;

Fig. 8 is a fragmentary cross sectional view illustrating the manner in which a fabric panel may be assembled

2

with a metal frame member similar to the frame member shown in Fig. 6 but embodying a slightly modified form of this invention; and

Fig. 9 is a fragmentary cross sectional view similar to Fig. 7 and showing how the fabric gripping metal portion of the metal frame member shown in Fig. 8 may be deformed to its ultimate fabric retaining position.

Referring now more specifically to the drawings wherein like parts are designated by the same numerals throughout the various figures, a structure 10 embodying the preferred form of the present invention is shown in Figs. 1 through 4. The structure 10 includes a sheet metal frame member 12, a covering fabric panel or section 14, and a member 16 mounted on the frame member for securing the fabric panel to the frame member. In instances when the structure 10 is to be utilized in a box spring unit frame of the type shown in the aforementioned co-pending application, it may be desired to provide the structure with a dust protecting fabric panel 18 for covering the bottom of the box spring unit frame, not shown, which dust protecting panel may also be secured to the frame member 12 by the securing member 16.

The frame member 12 is formed from sheet metal and includes a web portion 20 and integral laterally extending flanges 22 and 24. A longitudinally extending mid-portion of the web 20 is provided with an inwardly formed channel section including inwardly bent portions 26 and 28 joined by a section 30. Various uses and advantages of the metal frame member 12 are fully set forth in the above mentioned co-pending application.

The member 16 is formed from sheet spring metal and includes a substantially flat longitudinally extending portion 32 which is secured to the flange 24 of the frame member by means of a plurality of spaced welds 34. The member 16 also includes a longitudinally extending section 36 which extends from the section 32 and flares outwardly or downwardly from the flange 24. The section 36 merges with an inwardly curved and reversely extending portion 38 which has a serrated free marginal edge or an edge provided with a series of closely spaced pointed teeth 40. The sections 36 and 38 of the securing member 16 are formed so that the teeth 40 are normally resiliently urged into contact or substantially into contact with the flange 24.

When assembling the fabric panel or section 14 with the frame member, the margin of the fabric panel is forced between the teeth 40 and the flange 24 as shown best in Fig. 3. It will be noted that the inward inclination of the teeth facilitates insertion of the fabric through

the restricted opening between the teeth and the flange whereupon the teeth dig into the fabric and positively prevent withdrawal of the fabric. The fabric may be easily inserted with the aid of any simple flat bladed tool such as the tool 42 shown in Fig. 2 as will be understood. The dust protecting fabric 18 is inserted into the securing member in the same manner as the fabric panel 14 and is shown best in Fig. 3. The teeth 40 are preferably formed so that they are long enough to pierce both of the panels 14 and 18.

Fig. 5 shows a slightly modified form of the present invention which is substantially similar to the above described structure as indicated by the application of identical reference numerals with the suffix "a" added to corresponding elements. This embodiment differs only in that the fabric panel 14a is provided with a marginal hem portion 44 which is sewn as at 46 and a wire 48 is inserted into the hem. The hem and the wire are then forced into the securing member 16a whereupon the wire is engageable with the inner surface of the teeth

40a. This structure has an advantage in that the margin of the fabric panel is even more securely retained in assembled relationship with the frame member and can-

not be removed without first manually bending the member 16 away from the flange 24a sufficiently to permit withdrawal of the wire.

In Figs. 6 and 7, there is shown another modified form of the present invention which is similar to the above described structure as indicated by the application of identical reference numerals with the suffix "b" added to corresponding elements. As will be seen by referring to the drawings, this embodiment differs primarily in that securing means 16b is formed integral with the flange 24b of the frame member. More specifically, the securing means 16b is provided by an extension of the flange 24b, which extension includes a portion 50 which is bent laterally outwardly or downwardly from the flange and a portion 52 which extends back toward the flange and provides a restricted opening for receiving the margin or hem of the covering fabric 14b. A free marginal portion 54 of the securing means is preferably flared outwardly to facilitate insertion of the covering fabric hem and the wire or rod enclosed in the hem through the restricted opening. Preferably, a plurality of teeth 56 are struck inwardly from and are spaced along the portion 52 for further closing the restricted opening and for positively preventing removal of the fabric from the opening.

In Figs. 8 and 9, there is shown an embodiment similar to the embodiment of Figs. 6 and 7 as indicated by the application of identical reference numerals with the suffix "c" added to corresponding elements. This embodiment differs in that the above described teeth have been omitted and the engagement between the portion 52c of the securing means and the wire or rod within the hem of the fabric may be relied upon for preventing disassembly of the fabric.

As shown best in Fig. 8, the portion 52c is initially formed so that the restricted opening provided thereby is relatively wide. This arrangement facilitates insertion of the fabric hem and wire or rod therein through the opening. After the hem and the wire or rod have been inserted through the opening, the portion 52c is collapsed inwardly as shown in Fig. 9 securely to hold the hem of the fabric covering.

From the above description, it is seen that the present invention has provided a novel structure whereby fabric panels may be quickly and easily connected with a metal frame member. In addition, it is seen that the novel fabric securing means of the present invention is adapted to retain the fabric evenly through its entire length whereby to reduce any possibility of unsightly bulges or wrinkles appearing in the fabric. It should also be noted that the fabric panel securing means described above not only serve to retain the fabric in assembled relationship with the frame member but also serve to reinforce the flange of the frame member since they extend for substantially the entire length of the flange.

While the preferred embodiments of the present invention have been shown and described herein, it is obvious that many structural details may be changed without departing from the spirit and scope of the appended claims.

The present invention is claimed as follows:

1. A structure for use in furniture and the like comprising a metal frame member, fabric panel means, means securing said fabric panel means and said frame member together, said securing means including a separate sheet metal member having a base portion secured to said frame

member, a second portion extending from said base portion generally in one direction and flaring away from said frame member, and a reversely bent portion extending from said second portion between said second portion and the frame member toward said base portion and substantially to said frame member and providing a restricted opening along a substantial length of said frame member, said fabric panel means having a portion thereof extending through said restricted opening and retained against removal from said opening by interengagement with said reversely bent portion.

5 2. A structure, as defined in claim 1, wherein said reversely bent portion terminates in a plurality of longitudinally spaced teeth impinging said fabric means, and wherein said fabric means includes a hem portion extending into said restricted opening, and an elongated member extending longitudinally within said hem portion and cooperating with said reversely bent portion for preventing removal of the hem portion from said restricted opening.

10 3. A structure for use in furniture and the like comprising a metal frame member, fabric panel means, means securing said fabric panel means and said metal frame member together, said securing means including sheet

15 metal means extending laterally from a portion of said frame member and generally in one direction, and teeth means integral with a free marginal portion of said sheet metal means and extending reversely generally in an opposite direction and between said sheet metal means and said frame member back toward and substantially to said frame member portion, said fabric panel means having a portion thereof inserted and retained between said frame member portion and said teeth means.

20 4. In a structure for use in furniture and the like the combination comprising a metal frame member, and means on said frame member for securing fabric panel means to the frame member, which fabric panel means extends from the frame member in one direction, said securing means including a separate sheet metal member extending along an outer surface of and secured to a substantial length of said frame member, said sheet metal member having a portion extending laterally from a section of said frame member and generally in a direction opposite from said one direction, and a retaining portion projecting from said laterally extending portion toward said frame member and between said laterally extending portion and said section reversely toward said one direction and substantially to said section to provide an elongated restricted opening between said frame member section and said retaining portion of the sheet metal member, into which opening a fabric panel means may be inserted and held by a free marginal edge of said retaining portion.

25 5. A structure, as defined in claim 4, which includes teeth means disposed along said free marginal edge and extending substantially to said frame member section for impinging fabric panel means being held by said retaining portion.
